UNITED STATES PATENT OFFICE.

RUSSELL B. KINGMAN, OF ORANGE, NEW JERSEY, ASSIGNOR TO USEFUL PRODUCTS COMPANY, OF WEST ORANGE, NEW JERSEY, A CORPORATION OF NEW JERSEY.

DOORCHECK.

Application filed September 7, 1927. Serial No. 217,896.

This invention relates to a simple construction of pneumatic door-check adapted to be mounted within a door-frame adjacent to the rabbet or stop against which the door 5 fits when closed, with its plunger projecting beyond the rabbet or stop into the path of closing movement of the door so as to receive the impact of the latter to check its movement sufficiently to prevent noisy slamming against the rabbet or stop and consequent jars.

It is the object of this invention to provide a pneumatic door-check, of the kind above mentioned, the construction of which has been greatly simplified and reduced to a minimum number of parts which may be produced and assembled at exceedingly low cost, so as to provide a device which may be marketed through chain stores, such as the so-called five and ten cent stores, and similar distributing agencies.

The invention has for a further object to provide in connection with a pneumatic door-check of the kind above referred to in which the construction and relation of the parts are such that no particular skill is required to properly position the device in operative relation to the door-frame and its rabbet or stop, and whereby when mounted on the frame the operative stroke of its plunger is automatically limited in such manner as to assure the production of an adequate air pocket at the rear end of its cylinder and intermediate such end and the piston so that no jamming of the piston against the rear end of the cylinder can occur, while at the same time an adequate elastic cushion produced by the compression of air within said air pocket is provided sufficient to assure checking of the door movement without preventing, however, its proper closing and latching.

Other objects of this invention, not at this time more particularly enumerated, will be clearly understood from the following detailed description of the same.

The invention is clearly illustrated in the accompanying drawings, in which:—

Fig. 1 is a side elevation of the novel door-check of this invention shown in operative relation to a door-frame and its rabbet stop and with the door open, said latter parts being shown in section; Fig. 2 is an end elevation of the device, looking in the direction of the arrow in Fig. 1; Fig. 3 is a

longitudinal section of the device shown in connection with a door-frame and its rabbit stop, and with the door shown in closed relation to the door-frame; Fig. 4 is a detail transverse section, taken on line 4—4 in Fig. 3; Fig. 5 is another transverse section, taken on line 5—5 in Fig. 1.

Similar characters of reference are employed in all of the hereinabove described views, to indicate corresponding parts. 65

Referring to said drawings, the reference character 1 indicates the cylinder of the device. This cylinder is drawn from metal stock to form an integral tubular body having a closed rear end 2 preferably of semi-spherical shape. The open end of said cylinder 1 is provided around its periphery with outwardly projecting circumferentially spaced apart lugs or tongues 3. The open end of said cylinder 1 is adapted to be closed by a combined cylinder head and supporting bracket of integral construction, the same comprising a head body 4, from one side of which extends, preferably in the plane of said head, a bracket arm 5 from the free end of which and at right angles to which projects a forwardly extending foot-piece or base 6 suitably perforated for the reception and passage of fastening screws 7; extending around the periphery of said head body 4 so as to terminate at each side of said bracket arm 5 is an annular rearwardly projecting skirt-flange 8; and said head body 4 is provided in properly spaced relation around the same and adjacent to its periphery with a series of slots or perforations 9. In order to stiffen the combined cylinder head and supporting bracket at the juncture of its bracket arm 5 and foot-piece 6, the latter parts are indented across their interior angle to provide integral stiffening or reinforcing ribs 10. Said head

stiffening or reenforcing ribs 10. Said head body 4 is provided with a central opening 11 to provide for the movement therethrough of a piston stem 12. Secured upon the inner end of said piston stem 12, against an enlargement or shoulder 13 with which the latter is provided, is a metal piston disk 14, having one or more notches 15 in its periphery to provide air-passage. Backed by said piston-disk 14 and secured by a retaining washer 16 over which the inner end of the piston stem 12 is riveted, is a cupped piston member 17 preferably made of leather or similar more or less flexible material. 100 105 110

After the forward or free end of the piston stem 12 is passed through the opening 11 of the head body 4, a flanged seating disk 18 is affixed to the outer extremity of the 5 piston stem 12, and secured in seated relation to and upon said seating disk 18 is a resilient buffer 19, preferably made of soft rubber.

After the piston structure and cylinder 10 head structure have been assembled together in the same manner and in the relation above indicated, a spiral compression spring 20 is seated within the closed end of the cylinder 1, and the piston-member 17 is entered 15 through the outer end of said cylinder and in engagement with said spring 20. The head body 4 is now engaged with the open portion of the cylinder by telescoping the skirt-flange 8 if the former over the latter, and with the lugs or tongues 3 of the cylinder 20 projecting exteriorly through the slots or perforations 9 of said head body 4, whereupon the free ends of said lugs or tongues are clinched over the latter, thus firmly and 25 securely uniting the various parts of the door-check structure in operative assembled relation.

The reference character 21 indicates a 30 door-frame provided with a rabbet or stop 22 against which the door 23 is stopped when moved to closed relation to the frame.

To mount the door-check device upon the door-frame 21 in operative relation to the door 23, the foot-piece or base 6 is placed 35 against the door-frame with its free edge aligned with the stop face of the rabbet 22; the foot-piece or base 6 is made of a predetermined distance of projection outwardly or forwardly of the head body 4, so that when 40 its outer edge is registered with the stop face of the rabbet 22 as above stated, the device will be automatically located in proper operative position, so that the operative inward stroke of the piston will be predetermined for the purposes already hereinabove 45 stated; this feature of my invention is of considerable importance since it allows the users, without any special mechanical skill, to attach or mount the device with full assurance that the same will be in 50 proper operative relation to the frame and its door, since the bracket itself provides a positioning guide adapted to so locate the head end of the cylinder rearward of the rabbet 22 that the inward thrust or operative 55 stroke of the piston stem is properly limited whereby an air pocket of adequate capacity is assured behind the piston member, and whereby the piston member can 60 not injuriously collide with the closed end of the cylinder.

In operation, as the door 23, in swinging closed strikes the exterior buffer end of the piston stem the piston member is caused to 65 travel rearwardly in the cylinder, and

against the spring 20 so as to compress the latter, and the air intermediate the piston member and closed end of the cylinder will be suddenly compressed, and by its compression will yieldably check the motion of the 70 door and reduce the same sufficiently to assure quiet closing against the rabbet or stop 22. When the door is opened, so that its pressure on the piston stem is released, the compressed spring 20 will cause the piston 75 member to move outward, the air entering behind the thus moving piston member through the notches 15 in the piston disk 14 and the flexible flange of the piston member yielding to such air flow; this movement 80 continuing until the piston and its stem regains normal outwardly moved position.

From the above description it will be apparent that door-check device according to this invention as above described, comprises 85 but few parts easily assembled, and involving a novel interconnected relation at a single end of the cylinder body of a combined cylinder head and supporting bracket, whereby a very strong and durable and yet 90 relatively inexpensive construction is furnished capable of being produced and marketed at exceedingly low cost.

Having thus described my invention, I 95 claim:

1. A pneumatic door-check comprising a sheet metal cylinder having an integral closed rear end, a combined sheet metal cylinder-head and supporting bracket, the open end of said cylinder having clinching lugs 100 projecting through and engaged on the external side of said cylinder-head, a piston-member slidable within said cylinder, a piston stem projecting exteriorly through said cylinder-head with its outer extremity 105 adapted to extend beyond a door stop of a door-frame and in the path of movement of a door toward said stop, and a compression spring intermediate the closed rearward end of said cylinder and said piston-member, said combined cylinder-head and supporting bracket being provided in connection with the latter portion with an integral base of predetermined forward extension to act as a gauge in locating the device 115 on a door frame and in proper relation to the door stop thereof.

2. In a pneumatic door-check, a sheet metal cylinder having an integral semi-spherical closed rear end; an integral combined sheet metal cylinder-head and supporting bracket, comprising a head-body, a laterally extending bracket arm, and a base extending from the extremity of said bracket arm at substantially right angles thereto; the open end of said cylinder having integral clinching lugs projected through circumferentially arranged apertures in said head-body and clinched exteriorly upon the same to unite the cylinder therewith; a pis- 130

ton-member slidable within said cylinder, thereof whereby the same serves as a gauge ¹⁰ a piston stem projecting exteriorly through in locating the device on a door-frame in said head-body, and having a buffer on its proper relation to the door stop thereof and free extremity; and a compression spring so as to predetermine the operative stroke of ¹⁵ said piston member.

5 intermediate the closed rearward end of said cylinder and said piston member, said base of the combined cylinder-head and supporting bracket being of predetermined forward extension relative to the head-body

In testimony, that I claim the invention ¹⁵ set forth above I have hereunto set my hand this 2nd day of September, 1927.

RUSSELL B. KINGMAN.
